SUPPORT ADAPTER FOR A DIGGER TOOTH

William W. Wilson, 6204 W. Canal Blvd.,
Shreveport, La. 71108

Filed July 1, 1966, Ser. No. 2,906

Term of patent 14 years

(Cl. D39—1)

FIG. 1

FIG. 2

FIG. 3

FIG. 4

FIG. 5

FIG. 6

FIG. 7

FIG. 8FIG. 9FIG. 1 is a perspective view of a support adapter for a digger tooth showing my new design,

FIG. 2 is a side view thereof,

FIG. 3 is a back view thereof taken on the line 3—3 of FIG. 2,

FIG. 4 is a back view thereof taken on the line 4—4 of FIG. 2,

FIG. 5 is a front view thereof,

FIG. 6 is a top view thereof,

FIG. 7 is a bottom view thereof,

FIG. 8 is an enlarged side view thereof with the broken line showing of a digger tooth indicated for illustrative purposes only, and

FIG. 9 is a front perspective view of this support adapter for a digger tooth showing a modification thereof.

I claim:

The ornamental design for a support adapter for a digger tooth, as shown and described.
